UNITED STATES PATENT OFFICE.

JOHN P. RADLEY, OF COLONIE, NEW YORK, ASSIGNOR TO CHARLES H. TURNER, OF ALBANY, NEW YORK.

DESIGN FOR A LAWN-RAKE HEAD.

SPECIFICATION forming part of Design No. 32,363, dated March 20, 1900.

Application filed November 13, 1899. Serial No. 736,876. Term of patent 14 years.

To all whom it may concern:

Be it known that I, JOHN P. RADLEY, residing on the Troy road, in the town of Colonie, county of Albany, State of New York, have 5 invented and produced a new and original Design for Lawn-Rake Heads, of which the following is a specification, reference being had to the accompanying drawing, forming a part thereof, in which the figure is a perspective 10 view.

The leading or material feature of my design consists in a lawn-rake head which is in cross-section concavo convex, is serrated along each edge, as at A, and at each end is provided with the sharpened projections C. C. 15 Along its concave surface I provide a series

of ribs B. A screen D is placed substantially at right angles to and extends from the concave side of the head of the rake and from one end to the other of the rake-head. 20

Having described my invention, what I claim as new, and desire to secure by Letters Patent, is—

The design for a lawn-rake head, as herein shown and described. 25

Signed by me at Albany, New York, this 3d day of November, 1899.

JOHN P. RADLEY.
